UNITED STATES PATENT OFFICE.

CONRAD LIEBRICH, OF PHILADELPHIA, PENNSYLVANIA.

TRUNK-LOCK HASP.

Specification forming part of Letters Patent No. 10,862, dated May 2, 1854; Reissued April 15, 1873, No. 5,352.

To all whom it may concern:

Be it known that I, CONRAD LIEBRICH, of the city and county of Philadelphia and State of Pennsylvania, have invented certain new and useful Improvements in the Construction of Hasps for Trunk and other Locks; and I do hereby declare the following to be a full, clear, and exact description of the construction and operation of the same, reference being had to the accompanying drawings, making a part thereof, in which—

Figure 1, represents a front view of the hasp Fig. 2, represents a rear view of the same Fig. 3, a similar rear view with the spring which holds the two parts forming the hasp removed. Fig. 4, represents a vertical central transverse section through the hinge.

20 Similar letters in the several figures denote like parts.

I am aware that hasps for trunks and other similar articles have been made with hinges, but in all these heretofore made the 25 hinges were not controlled, and the consequence was that, when the lid of the trunk dropped shut, the catch of the hasp would strike against the trunk frame, and frequently break them off, and always cut or damage the trunk. A still greater difficulty with the uncontrolled hinge when applied to self locking locks, is that when the lid of the trunk drops it is frequently locked by the jar of such accidental dropping. Another 30 serious objection to the present form of hasps, is that, the strain or tendency of the lid to open comes entirely upon the catch, which being slight and riveted to the hasp is not capable of sustaining any very great 35 force.

The object of my invention is to remedy both these serious objections, and may be said to consist first; in the application of a spring attached to one part of the hinge and 40 pressing or so acting against the other part, as that the hinged portion of the hasp will always stand in such inclined position, as to avoid striking the trunk frame in letting down the lid, and to prevent the hasp catch 45 from entering the lock, until pressed in against the action of the spring. Second, in setting the hasp catch in a solid projection cast with the hasp, which solid projection enters the lock sufficiently far to receive the 50 strain or tendency of the lid to open, thus

taking the force from the catch itself, and transferring it to the solid metal, which makes the hasp more substantial and less liable to be forced open.

To enable others skilled in the art to make 60 and use my invention, I will proceed to describe the same with reference to the drawings.

The hasp is cast or wrought in two pieces A, B, and for the purpose of lightness may 65 be cast partially hollow on the under side as seen by the double lines in Fig. 2. On the upper part A, of the hasp is attached a spring a, the point of which presses against the lower part B, so that said lower part will 70 always, unless the hasp is locked, stand as represented in Fig. 4. On said upper part A, are cast two recesses b, b, into which two journals or axes c, c, cast or wrought on the lower part B, rest and turn, being held 75 therein by the spring a. This without any farther fastening forms the hinge; and as the spring is on the under side of the hasp, and the pivot of the hinge solid or fast to the lower part of the hasp, the hinge or joint 80 cannot be separated without boring clear through the journals from outside to outside. This is important inasmuch as in ordinary hasps the joint or hinge is a weak point and often successfully assailed by burglars. The 85 lower part of the hasp is turned outward as seen in Figs. 1, 4, so that should the hasp or catch stick in the lock, there may be something to catch hold of to draw it out.

Another important feature in this spring 90 hasp is that, under ordinary circumstances, when used with spring or self locking locks, it is only necessary to turn the key and the hasp catch flies out of the lock itself. To those who have attempted to hold the lock 95 bolts back with key in one hand to draw and hold out the hasp catch with the other, and then raise the lid of the trunk, the convenience of the spring hasp will be very obvious.

In Fig. 4, d, represents the projection which is cast solid with the part B of the hasp the catch e, being riveted in it as seen in the drawing. This projection d, enters the lock or the escutcheon far enough to 105 catch against the lock plate and take the strain incident to the rising of the trunk lid into the solid metal, and relieving the catch e from a force which it is not well calculated to withstand.

Having thus fully described the nature of my invention what I claim therein as new and desire to secure by Letters Patent is—

1. The so combining of a spring with a hinged hasp as that the lower or hinged portion thereof shall stand off from the trunk, substantially in the manner and for the purpose described.
2. The placing of the hasp catch in a solid

projection which enters the lock with the hasp catch, and takes all the strain incident upon the tendency of the lid to open, and thus protect the catch itself substantially as described.

C. LIEBRICH.
